UNITED STATES PATENT OFFICE.

HENRI VICTOR JULES JOUFFRET, OF NEUILLY-SUR-SEINE, FRANCE.

SPARKING PLUG.

1,325,405.

Specification of Letters Patent. Patented Dec. 16, 1919.

Application filed June 10, 1918. Serial No. 239,252.

To all whom it may concern:

Be it known that I, HENRI VICTOR JULES JOUFFRET, engineer, a citizen of the French Republic, residing at Neuilly-sur-Seine, Department of Seine, France, have invented certain new and useful Improvements in Sparking Plugs, of which the following is a specification.

This invention relates to sparking plugs for internal combustion engines.

It has for its principal object the construction of articles of the class in question in such a manner that the gases entering the space at the lower part of the casing of the plug do not raise it to too high a temperature, the construction being moreover more simple, effective and economical than that of such devices as already in use.

The invention refers to that type of sparking plug, having one extremity of the casing, namely the one connected to the combustion chamber of the motor, to which the device is fitted, provided with a plurality of passages, adapted to put the interior of the said casing into communication with the combustion chamber of the motor, one of the passages, namely that where the ignition takes place, being relatively large in section, and the others relatively small and it consists in so constructing the device that the passages do not open directly into the interior of the casing but into a secondary chamber separated by a constricted portion on the interior from the said interior of the casing and in providing the said passages in an independent part extending into and fixed in the said casing.

In addition to the foregoing principal constructional features, which are preferably employed in combination, the invention comprises other features which will be more fully described hereafter.

It includes certain constructional embodiments of the said improvements, devices comprising the said improvement, as new articles of manufacture, and special parts suitable for their construction.

In order that the said invention may be clearly understood, I will now proceed to describe the same with reference to the accompanying drawing, which however is given merely by way of example.

Figure 1 of the said drawing is an axial

sectional view of a sparking plug constructed according to the invention.

55

Fig. 2 is a plan of the electrode block connected to the body portion of the said plug.

In the method of carrying out the invention represented in the drawing, I make the sparking plug with a casing *a*, in the interior of which is an insulated electrode *b* surrounded by an insulator *c*, and I mount the electrode *d* in the extremity of the casing *a* which screws into the motor so that it comes at a short distance from the extremity of the insulated electrode *b*.

It is desirable to prevent the gases as they pass into the interior *a*¹ of the casing—that is to say, between the insulator *c* and the inner wall of the casing—from having too high a temperature with the consequent effect of causing rapid deterioration of the insulator *c*. For this purpose I provide in that extremity of the casing *a*, which opens into the combustion chamber of the motor, a plurality of passages connecting the interior *a*¹ of the casing with the said combustion chamber, one of these passages *d*¹, namely the one in which the ignition takes place being of relatively large section 65 while the others *d*² are of relatively small section.

In addition to adopting the construction just explained, according to my invention, in place of causing the passages *d*¹ and *d*² to open directly into the interior *a*¹ of the chamber, I so arrange that they open into a secondary chamber *a*², provided in the cylindrical extremity of the casing, the chamber *a*² being separated from the chamber *a*¹ 75 by a constriction *a*³ on the interior.

Moreover, I prefer to provide the passages *d*¹ and *d*² in a piece or block projecting into or adapted to be inserted in the cylindrical extremity of the casing: and with this end 85 in view, I make the electrode *d* from a cylindrical block, the outer diameter of which is equal to the inner diameter of the extremity of the casing *a*.

In the said cylindrical block, I drill a central hole *d*¹, into the interior of which the point of the insulated electrode *d* extends when the parts are assembled, and I provide around the periphery of the said cylindrical block a plurality of grooves or recesses *d*². 100

I fix the said cylindrical block *d* in the

105

extremity of the casing a , either by forcing it into position, as shown, or I may provide it with a screw thread adapted to screw into a corresponding screw thread in the casing a .

In this way, I obtain a sparking plug in which the gases at a high temperature pass at each explosion both through the central passage d^1 into the interior a^1 of the chamber, and also through the passages d^2 of small section, and the gases in passing through these passages of small section become cool as if they had been passed through a metal trellis, the result being to lower the temperature of the gases in the interior a^1 of the chamber, the cooling effect being increased owing to the fact that the gases passing through the different passages are agitated and the flow broken up in passing through the constricted portion a^3 before penetrating into the interior a^1 of the chamber.

It is to be understood that the invention is not limited to the particular method of carrying the same into effect which has been more particularly described, but that it includes such modified constructions as come within a fair interpretation of my claims.

Claims.

30 1. A sparking plug comprising a casing for connection with the combustion chamber of the motor and a cylindrical electrode block fitted into the lower end of said casing and conforming in external diameter to the

internal diameter of the portion of the casing in which it is fitted, said block having a plurality of passages to establish communication between the combustion chamber and the interior chamber of said casing, said casing having a secondary chamber between said passages and said interior chamber and having an interior constriction between said secondary and interior chambers.

2. A sparking plug comprising a casing for connection with the combustion chamber of the motor and a cylindrical electrode block fitted into the lower end of said casing and conforming in external diameter to the internal diameter of the portion of the casing in which it is fitted, said block having a plurality of passages to establish communication between the combustion chamber and the interior of said casing and having said passages constituted by grooves formed in its periphery and by a central opening of relatively large section as compared with said grooves, said casing having a secondary chamber between said passages and said interior chamber and having an interior constriction between said secondary and interior chambers.

In testimony whereof I have hereunto set my hand in presence of two subscribing witnesses.

HENRI VICTOR JULES JOUFFRET.
